UNITED STATES PATENT OFFICE.

WILLIAM P. DALRYMPLE, OF CHICAGO, ILLINOIS.

TEMPERATURE INDICATION.

Application filed December 3, 1926. Serial No. 152,441.

This invention relates to improvements in thermal indicator as for automobile radiators.

The main objects of this invention are to provide a simple, reliable device for indicating certain operating conditions of an automobile engine and the like; to provide such a device which is suitable for being manufactured in large quantities without requiring accurate adjustments and calibrations; to provide such a device which is positive in its action, and in which a large movement of the indicating member may be obtained; and to provide such a device which is not materially affected by vibration, and which is not likely to get out of order.

This invention involves the application of a new principle in thermal indicators for automobile radiators. When spongy, absorbent material is exposed to vapors liberated at low temperatures, the vapors condense in the spongy material, forming a water plug and if air is trapped in a confined space above the water plug, then as the temperature of the vapor increases, the temperature of the plug increases, but there is no escape for the entrapped air above the plug and the pressure of this air is then available to operate an indicator even where the exciting cause is a free unconfined vapor below the plug.

An illustrative embodiment of this invention is shown in the accompanying drawings in which:

Figure 1 is an elevation of the indicator, mounted in a cap of an automobile radiator.

Fig. 2 is a cross section of the indicator.

Fig. 3 is a section taken on the line 3-3 of Fig. 2.

In this invention, an expandable element, preferably of a light frictionless construction, such as a bellows, is mounted in closed communication with a chamber having an inlet which is plugged with an absorbent material, preferably of a fine fibrous composition such as asbestos wool.

The moisture which is vaporized from the surface of the liquid, is absorbed by the plug, and carried through to the chamber above the plug, by capillary action. The moisture is condensed by the cooler walls of the chamber, so that a small amount of liquid becomes loosely confined therein. When the temperature is raised to the boiling point, expanding gases are rapidly released from the moisture or liquid, which causes a pres-

sure in the chamber, which is restrained by the moisture saturated plug. This pressure is communicated to the interior of the bellows and causes the bellows to expand. A suitable mechanical signalling device is connected to the bellows for operation so that the movement of the bellows actuates the signalling device.

Referring to the construction shown in the drawings, a housing is provided having a cup-shaped bottom 4 and flanged plate 5 which fits over the top of the portion 4, and a cover 6 which includes a hood 7 for housing the swinging semaphore member 8.

A stem, comprising the threaded tube 9, is sealed in the bottom member 4, and is threaded through a tapped hole in the radiator cap 10, of the automobile radiator 11. The bellows comprises the upper and lower flexible cup plates 12 and 13, which are joined at the edges, forming in effect an expandible diaphragm chamber. The lower plate 13 is brazed to the upper end of the tube 9, and is provided with a hollow stem 14, which opens into the tube. To provide a condensing pressure chamber, a coil 15, of copper wire fabric, is inserted in the upper end of the tube 9, and also serves as a backing for the asbestos wool plug 16, which is held in place in the lower end of the tube by means of a wire screen 17.

The semaphore member 8 is pivotally mounted in the housing and operatively connected to the bellows. The semaphore 8 is centrally pivoted to a lug 18, which is bent up from the material in the cover member 5 and the movement of the semaphore is limited by the ends striking the surface of the plate 5. The connection to the bellows comprises a looped wire 19, which is secured to the center of the plate 12, and engages, at the upper end, in a hole 20, which is provided in the semaphore member 8, quite close to the axis of movement.

When the bellows is collapsed, as shown in Fig. 2, one arm of the semaphore 8 covers the window 21, in the side wall of the hood 7; and, when the bellows is expanded, the semaphore is rotated to the opposite position, where the opposite end covers the opposite window 22.

The operation of the indicator may be gradual between wide temperature or pressure differences, or according to the tension on the looped spring wire 19 and the stops 110

for the indicator provided by plate 5, the operation of the indicator may be limited to take place only between comparatively close temperature or pressure points. For example, when the device is used for indicating the temperature of some part of the cooling system of an automobile, the only function that may be desired of the instrument is to indicate an excessively high temperature upon the failure of thermostatic or other temperature controlling devices of the cooling system to prevent excessive engine temperatures. Assuming that it is desired to have the indicator operate, that is, rock to the right, Fig. 2, only at near the boiling point of the water in the engine jacket, this may be arranged for by the air capacity design and resilience of the bellows formed by the flexible plates 12 and 13 and tension spring 19. The instrument is located at the upper part of the radiator and this space is occupied by splashing water, air and vapor, the vapor content of the space increasing according to the rise in temperature and, long before the water in the engine jacket is near the boiling point, vapor is condensed in the previous plug 16, thus sealing the air above the plug and in the bellows against escape downwardly through the plug, when expansion of the air takes place because of the rising temperature.

If the device is used in places where there is sufficient steam pressure to cause the steam to pass upwardly through the plug 16, the copper fabric coil 15 which is in metallic contact with a casing of the instrument then functions as a condenser causing moisture to drop down into the plug 16 and preserve its sealing function.

The pressure within the bellows at temperatures very much below the boiling point may, with a certain adjustment of the instrument, be insufficient to rock the indicator away from its normal setting as shown in Fig. 2, but when the engine cooling water is boiling, heat is given off very rapidly and is conducted to the upper portion of the radiator and to the instrument itself, thus causing an expansion of the air within the bellows sufficient to operate the indicator.

By the form of thermal motor shown, comprising the bellows and the plugged tube 9, which is substantially the inlet to the bellows, a very positive and reliable action is secured for indicating the boiling temperature. Therefore, no adjustment is required, since the semaphore arm 8 is merely moved from one stopped position to another, and the excess movement in the motor element is taken care of by the resilience in the parts, especially in the looped wire 19.

While but one illustrative embodiment of this invention has been shown and described, many alterations and omissions may be had without departing from the spirit of the in-

vention as defined in the following claims.

I claim:

1. In an indicator, a thermal motor comprising, a tube, an expansible chamber mounted on and enclosing the upper end of said tube, said chamber connected to the interior of the tube, indicating means responsive to the expansion of said chamber, a mass of wire fabric inserted in the upper end of the tube to form a condensing chamber, and a plug of asbestos wool in the tube below said mass.

2. An indicator comprising a housing having a hollow stem closed at the upper end, a bellows mounted on the stem and integrally connected therewith, a semaphore arm pivotally mounted in the housing and connected to the bellows for operation, and an absorbent plug in the lower end of the tube.

3. An indicator comprising a housing having a hollow stem mounted in the radiator cap, an expansible chamber mounted in the housing and communicating with the interior of said hollow stem, a signal arm movably mounted in the housing and connected to said expansible chamber, and an absorbent plug in the lower end of said stem for restricting the egress of pressure from said expansible chamber.

4. The method of indicating the temperature or pressure of a vapor bearing gaseous medium which consists in trapping a quantity of fluid by the condensation of moisture from said gaseous medium and utilizing the expansion or contraction of said quantity of fluid for indicating purposes.

5. In an indicator, a thermal motor comprising a hollow expansible chamber, an inlet communicating with said chamber for admitting a fluid thereto, and an absorbent plug adapted to become saturated with moisture, said plug being associated with said inlet in such relation as to restrain the egress of fluid pressure from said chamber when said plug is substantially saturated.

6. In an indicator, a thermal motor comprising a hollow expansible chamber, a movable member actuated by the expansion and contraction of said chamber, an inlet communicating with the interior of said chamber for admitting fluid thereto and an absorbent plug interposed between said inlet and atmosphere, said plug when approximately saturated operating to substantially seal said inlet against the egress of pressure from said expansible chamber.

7. An indicator of the class described comprising means for forming an enclosed space including a pressure responsive member, a passageway communicating with the interior of said enclosed space and serving to admit a gaseous fluid thereto, a pervious moisture condensing element in said passageway adapted to restrain the egress of fluid pressure from said enclosed space back through said

passageway, and indicating means operably connected with said pressure responsive member.

8. An indicator of the class described comprising means for forming an enclosed space including a pressure responsive member, a passageway communicating with the interior of said enclosed space and serving to admit air thereto, a mass of absorbent material in said passageway, condensing means in said passageway adapted to precipitate vapor condensate on said absorbent material for substantially saturating the same and thereby restraining the egress of fluid pressure from said enclosed space back through said passageway, and indicating means operably connected with said pressure responsive member.

9. An indicator of the class described comprising means for forming an enclosed space including a pressure responsive member, a passageway communicating with the interior of said enclosed space and serving to admit a gaseous fluid thereto, a pervious moisture condensing element in said passageway adapted to restrain the egress of fluid pressure from said enclosed space back through said passageway, indicating means operably connected with said pressure responsive mem-

ber, and restraining means for said indicator limiting its operation to a particularly predetermined change in pressure.

10. A fluid motor comprising an expansible chamber, an inlet through which fluid is admitted to said chamber, and a pervious moisture absorbing element associated with said inlet and through which said fluid must pass to said expansible chamber, said moisture absorbing element adapted upon substantial saturation to restrain counterflow of fluid pressure through said inlet and thereby serve as a closure valve for said inlet.

11. A fluid motor comprising an expansible chamber, an inlet through which fluid is admitted to said chamber, an absorbent plug in said inlet and through which said fluid passes to said expansible chamber, and condensing means in said inlet adapted to precipitate vapor condensate upon said absorbent plug, said plug adapted upon substantial saturation to restrain counterflow of fluid pressure through said inlet and thereby serve as a closure valve for said inlet.

Signed at Chicago this 24th day of November, 1926.

WILLIAM P. DALRYMPLE.
